UNITED STATES PATENT OFFICE.

VICTOR E. HAAS, OF TOLEDO, OHIO, ASSIGNOR OF ONE-HALF TO SAMUEL E. STARR, OF TOLEDO, OHIO.

CARBURETER.

1,342,107.

Specification of Letters Patent.

Patented June 1, 1920.

Application filed April 10, 1918. Serial No. 227,691.

To all whom it may concern:

Be it known that I, VICTOR E. HAAS, a citizen of the United States, and a resident of Toledo, in the county of Lucas and State of Ohio, have invented a certain new and useful Carbureter; and I do hereby declare the following to be a full, clear, and exact description of the invention, such as will enable others skilled in the art to which it appertains to make and use the same, reference being had to the accompanying drawing, and to the characters of reference marked thereon, which form a part of this specification.

15 The object of the invention is to provide an efficient mixer and fuel vaporizer. Means is provided whereby a perfect mixture will be produced when the engine is idling or running at a slow speed, as when the engine 20 is running at a higher speed, and will automatically adjust itself to the rate of speed of the engine.

25 The invention may be contained in vaporizers and carbureters of different forms to be used for a great variety of purposes, and yet such structures will come within the purview of the claims hereinafter appended. For purposes of showing the utility of the invention, I have selected one form of construction containing the invention and shall 30 describe the same hereinafter. The form of construction selected is illustrated in the accompanying drawings.

35 Figure 1 of the drawings is a side view of the carbureter shown partly broken and partly in section. Fig. 2 is a sectional view of the carbureter taken on line 2—2 indicated in Fig. 1. Fig. 3 is a broken view showing means for adjusting one of the outlets for the fuel.

40 1, Fig. 1, is the main body portion or supporting part of the carbureter. It is provided with a coupling flange 2. It has an air inlet 3 and an outlet 4 that leads to the 45 intake manifold of an engine. It is provided with a butterfly valve 5 which is connected with a suitable arm 7 for opening and closing the valve 5 and consequently the volume of the gas from the carbureter may be varied. The main body portion is also provided with a flange 8 on which is threaded a cap 9. The cap 9 is provided with a depending pocket 10 into which is threaded a sleeve 11. The sleeve 11 is provided with 55 a knurled head 12 for adjusting the posi-

tion of the sleeve 11 in the cap 9. The packing material and the packing nut 13 may be also threaded in the cap 9 to prevent any leakage by the sleeve 11. The lower end of the pocket 10 is provided with a flange 14 60 forming a socket in which is located a disk 15. The disk 15 is normally pressed against the bottom of a socket by means of the spring 16 which is located intermediate the disk 15 and the upper end of the sleeve 11. 65 The sleeve 11 may be threaded to a greater or less extent into the gap 9 to adjust the pressure of the spring on the disk 15.

70 The bottom of the pocket 10 is provided with an opening 17 through which extends a pin 18 having a diameter considerably smaller than the diameter of the opening 17. The upper end of the pin 18 is normally located at a short distance from the disk 15 and consequently after the pin 18 has 75 been raised through the short distance, it will then press against the disk 15.

75 Further upward movement of the pin 17 will be resisted by the tension of the spring 16 located in the sleeve 11. The pin 18 may 80 be surrounded by a spring 90 that is located between the disk and the shoulder at the lower end of the pin. The spring performs no function except to prevent sticking of a movable valve member 22.

85 The interior of the cap 9 communicates with the source of fuel supply through the fuel inlet 19. The fuel passes to the under side of a filter 20 which is secured in position by being clamped between the upper 90 end of the flange 8 and the cap 9. The fuel then passes up through the filter 20 and over the upper edge of a sleeve 21 formed in the carbureter body in which is located the needle valve 22. The needle valve 22 is 95 provided with a long conical shaped needle 23 and a short conical portion 24. The bottom of the sleeve 21 is formed so as to fit the long needle portion 23 and the short conical portion 24 and thus it forms seats 100 for these portions of the valve. The body portion of the valve 25 is made quadrilateral or winged in order to form spaces between the valve and the inside surface of the sleeve 21 and yet provide means for guiding the 105 valve in its vertical movements. The needle valve normally rests in its seat formed in the bottom of the sleeve 21. It is opened by a valve 26 that is located below the lower end of the valve 22. The valve 26 is located 110

in a sleeve 27 that surrounds and is clamped to the depending sleeve 21, the upper end of the sleeve 27 being slotted on one side thereof and being provided with ears 28 which may be clamped together by means of a screw 29.

The valve 26 is provided with a stem 30 that is located in a movable sleeve 31 which is also located in a recess formed in the sleeve 27. The stem 30 is made square in cross section or winged in order that spaces may be formed between the stem 30 and the inner surface of the sleeve 31 and yet means will be provided for guiding the movements 10 of the stem 30 in the sleeve 31. The valve 26 seats upon a conical seat formed on the upper end or edge of the sleeve 31. The stem 30 may be raised relative to the sleeve 31 and consequently the valve 26 may be 15 opened by the operation of a lever 32, which when moved operates a pin 33 against the pressure of the spring 34 which is located intermediate a washer 35 located on the end of the pin 34 and a recess formed in a cylindrical cup 36 that is threaded on to the body portion 1 of the carburetor. The pin 33 lifts an air valve or disk 37 and at the same time the valve 26 is opened, movements 20 of the pin 33 being communicated through a boss 38 formed on the upper side of the disk 37. When the valve 26 is lifted, the valve 22 is also lifted so as to open the valves. The gasoline or fuel passes down over the upper edge of the sleeve 21 by the 25 valve 22 and into the chamber formed below the end of the sleeve 21 and in the sleeve 27 and through the sleeve 31 and by the stem 30 of the valve 26. It passes over the boss 31 and spreads itself over the disk 37. 30 The disk 37 is inverted saucer or cone shaped so that the fuel passes down over its surface. The engine or other suction means having started, air is drawn through the openings 39 formed in the lower end of the 35 cup 40 which is formed in the bottom of the cylindrical cup 36 and is covered by the disk 37. Air enters beneath the conical disk 37 and passes outward from the cup 40 toward the edge of the disk 37 and catches 40 and vaporizes the gasoline that is distributed over the surface of the disk 37 and also that which passes over its edge. It thus mixes with the vapor of the fuel as it passes through the annular chamber 41 that 45 communicates with the outlet 4 of the carburetor.

A lever 32 may be supported by a suitable frame or pair of ears 42 that may be secured to the cylindrical cup 36 in any suitable way.

The valves 26 and 22 may be but slightly opened by the operation of the lever 32 but may be further opened by the difference in pressures produced above and below the 60 disk 37 that is produced by the suction of

the engine or other device. The valve 22 may thus be quite freely opened before the stem 18 strikes the disk 15 against which the relatively heavy spring 16 is pressed. Further movement is prevented by the 65 spring 16. The disk 37 will thus be lifted and consequently the valves 26 and 22 will be opened in proportion to the difference in pressures produced on the upper and lower surfaces of the disk 37, that is, in proportion to the rate at which the engine is moved. By this arrangement is produced a delicate 70 adjustment for giving the proper supply of fuel to the engine when it is idling. When, however, the engine is running at a higher 75 rate of speed, the spring 16 will come into play by the operation of the valve 43 and regulate the fuel supply, except as the valves 26 and 22 are positively opened by the operation of the lever 32. Automatic control 80 of the fuel supply according to the demand of the engine is thus also obtained by the suction which is produced on the inverted cup shaped valve 43 which moves over the lower end of the sleeve 27. The inverted 85 cup shaped valve 43 operates upon a pair of levers 44 fulcrumed in a channel formed in the end of the sleeve 27. The edge of the valve 43 presses against the outer ends of the levers 44. The inner ends of the levers 90 44 operate upon the end of the sleeve 31 which moves in the recess formed in the end of the sleeve 27 and against the spring 45 which is located intermediate a flange formed on the lower end of the sleeve 31 95 and the bottom of the recess formed in the end of the sleeve 27. The valve 43 is held against a depending flange 46. The edge of the depending flange 46 forms a seat for closing communication between the chambers formed above and below the valve 43. Suction produced by the engine operates to pull the valve 43 down and to operate on the levers 44 to lift the sleeve 31 which also 100 operates to lift the valve 22 against the tension of the spring 16. The valve 22 will thus be lifted so as to not only further remove the conical portion 24 of the valve from its seat, but also to move the needle portion 23 through the opening formed in 105 the lower end of the sleeve 21 and thus allow more or less of the fuel to pass into the chamber below the end of the sleeve 21 according to the amount of the suction produced by the engine. As the sleeve 31 and 110 the valve 37 is raised the valve 37 is raised, that is, the valve 37 follows the sleeve 31 up in its upward movement while the valve 26 is closed and in contact with its seat on the end of the sleeve 31. The valve 26 thus 115 120 gives an auxiliary or additional supply of air to the engine. The valve 37 is opened at a very low difference of pressure and the valve 43 is opened at a greater difference of 125 pressure and upon opening of the valve 37 130

the gasoline is admitted directly into the chamber below the valve 43 which closes the chamber and when the engine is speeded up the gasoline enters above the valve 43 while 5 the valve 37 further opens and forms an auxiliary air supply to the carburetor.

The sleeve 27 is provided with a plurality of openings 47. A sleeve 48 surrounds the sleeve 27 and is also provided with registering openings 49. The sleeve 48 may be 10 adjusted in its position on the sleeve 27 to vary the openings 47 and 49. A pin 50 is threaded into a boss 51 formed on the sleeve 48 and is thus connected to the sleeve 48. 15 The pin is provided with a handle 52 that may be shifted so as to move the pin 50 and the sleeve 48. The pin extends through the slot 53. The slot 53 is closed by an oblong plate which is about twice the 20 length of a slot so that the slot is covered in all positions of the pin, the plate lying against the carburetor wall. When the handle 52 is shifted, the openings 49 are also 25 shifted relative to the openings 47. When the valve 22 is opened by the operations of the valve 43, the fuel passes down through the sleeve 21 and into the chamber beneath the sleeve 21 and out through the openings 47. The flow however is regulated by the 30 position of the handle 52. The fuel then passes down over the sleeve 27 and onto the upper surface of the valve 43. The upper surface of the valve 43 is made conical in form and the fuel spreads itself over the 35 surface and passes beneath its seat 46 and down over the side of the cup shaped valve into the cup 36. Also the air passes in through the inlet 3 and over the surface of the cone shaped valve 43 and beneath the 40 depending flange 46 and down over its side, operating to vaporize and mix with the fuel as it passes into the cup 36.

To describe the construction with great particularity the valve 37 if attached to the 45 stem 33, has a weight of about one ounce. The valve 37 has a diameter of $1\frac{1}{16}$ inches. The spring 34 when coiled is $\frac{1}{2}$ inch long and has an outside diameter of $\frac{1}{4}$ inch. It 50 has seven coils. The maximum resistance on $\frac{3}{16}$ compression is about $1\frac{1}{4}$ ounce. The wire is of a phosphor bronze having a length about $4\frac{1}{2}$ inches and a gage of 25 B. & S. The valves 22 and 26 have an inclusive 55 weight of $\frac{1}{2}$ ounce. The spring 90 has four coils $\frac{1}{4}$ outside diameter and is formed of phosphor bronze wire 25 B. & S. gage and is $2\frac{7}{8}$ inches long. The maximum resistance is $\frac{1}{2}$ ounce. The maximum resistance during 60 opening the fuel valve through the operation of the valve 37 is $3\frac{3}{4}$ ounces. The opening area under the valve 37 is about $1\frac{1}{8}$ diameter and the carburetor referred to is designed for a four cylinder engine, $3\frac{1}{2}$ bore, four inch stroke. The resistance of the 65 valve 37 including the spring 34 at starting

the engine is about two ounces. When the valve has raised $\frac{5}{16}$ inch the resistance is about $3\frac{1}{2}$ ounces.

The weight of the valve 43 is two ounces. Its diameter is $1\frac{3}{4}$ inches. The spring 45 70 is one inch long and is $\frac{3}{8}$ inch outside diameter. The wire is 8 inches long, has seven coils and is formed of phosphor bronze No. 20 B. & S. gage. The resistance of the spring 45 at $\frac{3}{16}$ inch compression is about 75 ten ounces. The leverage of the valve 43 through the lever 44 is about three to one, thus acting against the spring 45 giving a resistance of about $3\frac{1}{2}$ ounces when the valve leaves its seat. The spring 16 which 80 also operates against the movement of the valve 43 is $1\frac{1}{4}$ inches long, $\frac{3}{8}$ inches in diameter, has twelve coils and a resistance from zero to about four pounds. It is formed of a phosphor bronze wire No. 17 B. & S. gage. 85 The wire is $12\frac{3}{4}$ inches long. The opening at the point where the valve 43 seats is $1\frac{1}{2}$ inches and the size of the main air intake 3 is $1\frac{1}{8}$ inches.

The cup 36 is divided into two chambers 90 that are separated by a depending apron or baffle 55. The baffle 55 is a cylindrical member that is threaded onto a depending flange 56 formed on to the body portion 1 of the carburetor. The baffle 55 extends to near 95 the bottom of the cup 56 and thus directs the fuel and the air to the bottom of the cup 36 giving opportunity and causing the air to thoroughly mix with the fuel. From the bottom of the cup 36 the air and vaporized fuel pass upward through the chamber 100 41 that surrounds the apron 55 and out through the outlet 4 and thus are thoroughly mixed.

If desired, the cup 36 may be provided 105 with openings 57 that are closed by a glass cylinder 58 which may be sealed by packing rings 59 located at the ends of the glass cylinder 58 and intermediate the cylinder and the body portion 1 of the carburetor in 110 the one case, and between the end of the cylinder 58 and the bottom of the cup 36 in the other case.

I claim:

1. In a carburetor for an internal combustion engine, the carburetor having a main air intake passageway and an auxiliary air intake passageway, air valves for controlling the movement of the air through the passageways, the carburetor having a fuel passageway, a pair of fuel valves for controlling the movement of the fuel into the carburetor, one of the fuel valves operating to direct the fuel from the fuel passageway into one of the air passageways and onto 120 the movable member of the main air valve when in one position and onto the auxiliary air valve when in another position and operated by the auxiliary air valve and the main valve. 125 130

2. In a carbureter for an internal combustion engine, the carbureter having a main air intake passageway and an auxiliary air intake passageway, air valves for controlling the movements of the air through the said passageways, the carbureter having a fuel passageway, a pair of fuel valves for controlling the movement of the fuel and operated by the air valves, both of the fuel valves opened by the auxiliary air valve and one of the fuel valves further opened and the other of the fuel valves closed by the main air valve.
3. In a carbureter for an internal combustion engine, a main air intake passageway and an auxiliary air intake passageway, a sleeve extending through the main air intake passageway, a source of fuel supply connected with the sleeve, a pair of fuel valves located in the sleeve, the main air valve surrounding and guided by the sleeve passageway extending through the wall of the sleeve and located above the main air valve, one of the fuel valves located above the sleeve wall passageway, the other fuel valve located below the passageway of the wall of the sleeve, and operatively connected to the first fuel valve to open the fuel valve and operatively connected to the auxiliary air valve to open the fuel valves
- and a movable seat member operatively connected to the main air valve for closing the second fuel valve.
4. In a carbureter for an internal combustion engine, a fuel valve, an adjustable spring member for controlling the fuel valve, an air inlet valve connected to the fuel valve, and operated according to the suction of the engine for opening the fuel valve until further opening of the fuel valve is prevented by the spring member, a second air valve for further opening the fuel valve according to the suction of the engine.
5. In a carbureter for an internal combustion engine, a fuel valve, an adjustable spring pressed member normally located at a point removed from the fuel valve, an air inlet valve connected to the fuel valve, and operated according to the suction of the engine for opening the fuel valve until further opening of the fuel valve by the said air valve is prevented by the spring member, a second fuel valve also opened by the air inlet valve, a second air inlet valve for further opening one of said fuel valves and for closing the other of said fuel valves.

In testimony whereof, I have hereunto signed my name to this specification.

VICTOR E. HAAS.
